UNITED STATES PATENT OFFICE.

ABEL T. ATHERTON, OF BAYSIDE, RHODE ISLAND.

DESIGN FOR A GRID-BAR FOR COTTON OPENERS AND LAPERS.

SPECIFICATION forming part of Design No. 35,719, dated February 11, 1902.

Application filed December 26, 1901. Serial No. 87,879. Term of patent 7 years.

To all whom it may concern:

Be it known that I, ABEL T. ATHERTON, a citizen of the United States, residing at Bay-side, in the county of Kent and State of Rhode Island, have invented and produced a new and original Design for Grid-Bars for Cotton Openers and Lappers; and I do hereby declare the following to be a full, clear, and exact description of the same, reference being 10 had to the accompanying drawings, forming a part thereof.

In the drawings, Figure 1 represents a perspective view of the bar. Fig. 2 shows a cross-section of the bar, taken on line 2 2 in 15 Fig. 1.

My design consists of a triangular bar of the following shape in cross-section: Two of the sides of the triangle are made at an angle of about one hundred and twenty degrees 20 to each other, with the corner at the junction of the sides rounded, and the lengths of the

sides are about as four is to five. The third side of the triangle is a straight line from the outer edge of one side to the outer edge of the other side. On the narrowest side *b* of 25 the triangle, at about one-third of the distance in from the sharp edge, I place a row of sharp tapering points *a*, inclined at an angle of about fifty or fifty-five degrees to the line of the side *b*, on which they stand. The 30 ends of the bar are made about square to the sides.

What I claim is—

The design for a grid-bar for cotton openers and lappers, herein shown and described. 35

In testimony whereof I affix my signature, in presence of two witnesses, this 20th day of December, 1901.

ABEL T. ATHERTON.
